UNITED STATES PATENT OFFICE.

DANIEL MCKINNON, OF WAPPINGER'S FALLS, NEW YORK, ASSIGNOR TO
ELIAS BROWN, OF SAME PLACE.

IMPROVEMENT IN HEAD-BANDS.

Specification forming part of Letters Patent No. 142,169, dated August 26, 1873; application filed
June 21, 1873.

To all whom it may concern:

Be it known that I, DANIEL MCKINNON, of Wappinger's Falls, in the county of Dutchess and State of New York, have invented a new and useful Improvement in Ornamental Head-Bands, of which the following is a specification:

The drawing is a perspective view of my improvement, showing its construction and practical application.

This improvement relates to an article of apparel especially applicable to the binding and dressing of the hair. The invention consists in an ornamental head-band provided with one or more hooks, substantially as hereinafter shown and described.

The band A is made, preferably, in one piece, in the form of a bow, and should be composed of a material that will possess, when finished, some degree of elasticity. The band may be composed of horn, rubber, or any other suitable material, and its extremities are to be provided with hooks *a a a*, the office of which

is to hook into the hair of the wearer, so as to bind and ornament the same, as indicated in the drawing. The edges and front of the band may be adorned by any suitable carvings or ornaments to suit the taste of the wearer. I have stated that the band is to be finished with one or more hooks, *a*; although one hook might answer a useful purpose, I prefer to use three hooks, as shown.

I am aware that side combs have been connected by springs, and this I do not claim; but

Having thus described my invention, I claim, and desire to secure by Letters Patent, as an improved article of manufacture—

An ornamental head-band provided with hooked teeth, substantially as herein shown and described.

DANL. MCKINNON.
